UNITED STATES PATENT OFFICE

165,728

PUMP

George H. Zimmer, Jr., Springfield, Ohio, assignor
to Robbins & Myers, Inc., Springfield, Ohio, a
corporation of Ohio

Application October 18, 1950, Serial No. 12,611

Term of patent 7 years

(Cl. D65—1)

To all whom it may concern:

Be it known that I, George H. Zimmer, Jr., a citizen of the United States of America, residing at Springfield, in the county of Clark and State of Ohio, have invented a new, original, and ornamental Design for a Pump, of which the following is a specification, reference being had to the accompanying drawing, forming a part hereof, and in which:

Figure 1 is a perspective view of a pump, according to my design as seen from the driven end thereof.

Figure 2 is a perspective view of the same as seen from the opposite end.

I claim:

The ornamental design for a pump, substantially as shown.

GEORGE H. ZIMMER, JR.
